UNITED STATES PATENT OFFICE.

WILLIAM A. HOFFMAN AND GEORGE GOSCH, OF EAU GALLIE, FLORIDA.

MACHINE FOR STRETCHING WIRE-CLOTH ON DOOR OR WINDOW FRAMES.

SPECIFICATION forming part of Letters Patent No. 783,786, dated February 28, 1905.

Application filed March 25, 1904. Serial No. 200,058.

To all whom it may concern:

Be it known that we, WILLIAM A. HOFFMAN and GEORGE GOSCH, citizens of the United States, residing at Eau Gallie, in the county 5 of Brevard and State of Florida, have invented certain new and useful Improvements in Machines for Stretching Wire-Cloth on Door or Window Frames, of which the following is a specification.

10 This invention appertains to means for stretching fabric, such as wire-cloth, upon frames in the manufacture of screen-doors, windows, and the like.

In its organization the machine comprises 15 a table for supporting the door or window frame, means for supporting a bolt of the goods or screen-cloth at one end of the table, a clamp for holding the screen-cloth when spread upon the frame, operating means for moving the 20 frame to place the screen-cloth under tension, and a detent mechanism for holding the operating means after the screen-cloth has been tightened and during the operation of securing the same to the frame.

25 The invention consists of the novel features, details of construction, and combinations of parts, which hereinafter will be more particularly set forth, illustrated, and finally claimed.

30 In the accompanying drawings, forming a part of the specification, Figure 1 is a perspective view of a machine embodying the invention. Fig. 2 is a transverse section on the line 2 2 of Fig. 1. Fig. 3 is a view of the machine inverted. Fig. 4 is a longitudinal section on the line 4 4 of Fig. 3 looking in the direction of the arrow. Fig. 5 is a cross-section of the machine on the line Z Z of Fig. 3.

35 Corresponding and like parts are referred 40 to in the following description and indicated in all the views of the drawings by the same reference characters.

The table or stand may be of any construction and size, according to the character of 45 work. As shown, the stand comprises the bed or top 1, side pieces 2, legs 3, and cross-pieces 4. The parts may be of any suitable

material, such as metal or wood or a combination thereof. Standards 5 are provided at one end of the table and are notched in their 50 upper ends to receive the end portions of a bar 6, upon which the bolt or roll 7 of wire-cloth or like goods is mounted.

A clamp is arranged adjacent to the bolt or roll 7 and comprises upper and lower bars 8 55 and 9 and cam-levers 10, the latter being mounted upon pins 11, supported in uprights 12, projected upward from the side pieces 2. The clamp bars or members 8 and 9 may be of any suitable material, metal being preferred, and having their inner or clamp faces provided with yielding material, such as wood and rubber. One of the clamp-bars, as 8, has its lower portion provided with a wooden strip 8^a, and a covering 9^b, of rubber or leather, is 60 carried by the lower bar 9, which also has its upper surface provided with a wooden strip 9^a. By having the clamp-faces of the members 8 and 9 clothed with yieldable material the screen-cloth is prevented from injury and held 65 from slipping when the goods or fabric is subjected to tension, as in the act of stretching. Springs 13 are interposed between the clamp members 8 and 9 to force them apart when the cam-levers 10 are moved, so as to effect a 70 release of the goods. The clamp is vertically adjustable as a whole, thereby insuring positive and certain action of the cam-levers 10 when thrown downward at their free ends, so as to advance the bar 8 toward the bar 9 when it 75 is required to grip the goods. For adjusting the clamp set-screws 14 are provided and are threaded into brackets 15, extended inward from the side pieces 2. The end portions of the set-screws are reduced or provided with 80 pins 16, which pass through the clamp member 9 and enter the clamp member 8 and upon which are mounted the springs 13. A washer 17 is mounted upon the shoulder at the base of the reduced portion 16 and sustains the end thrust 85 of the set-screw.

A plate 18 is arranged beneath the bed or top 1 and is mounted for longitudinal movement in cross-pieces 19. The front end of

the plate 18 is widened, as shown at 20, and upturned, as shown at 21, to form a shoulder or stop for engagement with the frame 22, upon which the screen-cloth 23 is to be secured. 5 The part 18 constitutes a tension device, as it is the means for moving the frame 22 when it is required to stretch the wire-cloth thereon. An operating-lever 24 is arranged beneath the bed or top 1 and extends transversely of the machine and is pivoted thereto at a point between its ends and is loosely connected to the tension device 18. The end portions of the lever 24 project beyond opposite sides of the machine, thereby enabling the operator to 10 actuate the same from either side of the machine, as may be most convenient. A dog 25 is pivoted to a side of the machine and is provided with a plurality of teeth, any one of which is adapted to engage with the adjacent 15 end of the lever 24 and hold the same in the required position. To admit of disengaging the dog 25 when the operator is upon the opposite side of the machine, a rod 26 extends transversely of the machine and is journaled thereto and is provided at one end with an arm 29 to engage with the tailpiece of the dog 25 and at its opposite end with an operating-arm 27, which is normally supported by a pin 28, so as to hold the arm 29 away from 20 the part 25. In the event of the operator being upon the side of the machine opposite to that provided with the dog 25 and it is required to release the latter from the operating-lever 24 the arm 27 is moved, thereby 25 rocking the rod 26 and correspondingly moving the arm 29, which is brought in contact with the tailpiece of the dog 25 and frees the latter from the operating-lever, as will be readily comprehended. 30 In the operation of the machine a bolt or roll of wire-cloth is slipped upon the bar 6 and the latter mounted in the standards 5. The frame 22 to be covered is placed upon the bed or table, and a portion of the wire-cloth sufficient to cover the same is drawn 35 from the roll 7 and is tacked or otherwise secured to the end of the frame remote from the roll 7, care being taken to pass the wire-cloth 23 between the members 8 and 9 of the clamp. The levers 10 are now operated so as to grip the wire-cloth at a point between the frame 22 and roll 7, after which the lever 24 is operated so as to move the bar 18, and its 40 projecting portion 21 coming in contact with the end of the frame 22 adjacent to the clamp moves said frame away from the clamp, thereby placing the wire-cloth under tension, the operating-lever being held in the required position by engagement of the dog 25 there- 45 with. The wire-cloth is now secured to the frame 22 in the usual or any determinate way, after which the operating-lever 24 is released and the wire-cloth cut close to the 50

frame, when the machine is in position for a repetition of the operation, the tension device 65 being returned to a normal position and the clamp loosened, so as to release the wire-cloth to admit of it being drawn freely from the roll preliminary to being attached to the next frame to be covered. 70

Having thus described the invention, what is claimed as new is—

1. In a machine of the character described, the combination of a support for the frame to be covered, a clamp for holding the goods, a 75 tension device, an operating-lever for actuating the tension device, a dog for holding the operating-lever in the required position, and means for effecting release of the dog and operable from the side of the machine opposite 80 that provided with the dog, substantially as set forth.

2. In a machine of the character described, the combination of a stand, a clamp for holding the goods, a tension device for moving 85 the frame to which the goods is to be applied, said tension device consisting of a longitudinally-movable bar having a projecting stop to come in contact with the work, an operating-lever for moving said bar, and means for 90 holding the operating-lever in the adjusted position, substantially as set forth.

3. In a machine of the character described, the combination of a stand, means for supporting a roll of goods, a tension device for 95 the work, and a clamp, the same comprising complementary members and coöperating cam-levers, substantially as set forth.

4. In a machine of the character described, the combination of a stand, means for supporting a roll of goods, a tension device for 100 the work, a clamp for holding the goods, and means for adjusting the clamp with reference to the clamp-operating means, substantially as set forth. 105

5. In a machine of the character described, the combination of a stand, means for supporting a roll of goods, a tension device for the work, a clamp for holding the goods, set-screws for adjusting the clamp with reference 110 to the clamp-operating means and having reduced portions extended across the space formed between the clamp members, and springs mounted upon said reduced portions to effect separation of the clamp members, 115 substantially as set forth.

6. The herein-described machine for the purposes set forth, the same comprising a stand, means at one end of the stand for supporting a roll of goods, a clamp adjacent to the goods-supporting means for holding the goods, means for adjusting said clamp, a tension device comprising a longitudinally-movable bar having a projecting stop for engagement with the work, an operating-lever for 120 said bar having its end portions projected be- 125

yond opposite sides of the stand, a dog at one side of the machine for engagement with the operating-lever to hold it in an adjusted position, and means for releasing said dog and ar-

5 ranged to be operated from the side of the machine opposite to that provided with said dog, substantially as set forth.

In testimony whereof we affix our signatures in presence of two witnesses.
